UNITED STATES PATENT OFFICE

2,089,007

CLOSURE FOR BOTTLES AND JARS

William G. Skutch, Toledo, Ohio, assignor to
 Owens-Illinois Glass Company, a corporation
 of Ohio

Application April 21, 1932, Serial No. 606,702

2 Claims. (Cl. 215—43)

The present invention relates to improvements in closures for bottles and jars and more particularly to closures consisting of inner and outer metal caps secured together. In this type of closure the inner cap is provided with attaching means intended for holding engagement with threads or the like on bottles or jars, while the outer cap is perfectly smooth, providing for suitable surface decoration.

10 The principal object of the present invention is the provision of simple and effective means to insure against relative rotation of the inner and outer caps after they have once been assembled. The objections to such relative rotation of these 15 caps while the closure is being applied to or removed from a container, are entirely obvious.

Another object is the provision of means whereby the skirt or flange portions of the inner and outer caps may be securely locked together without 20 to any degree distorting the screw threads or other attaching means provided on the inner cap. To this end the lower margin of the inner cap is deformed to provide an irregular contour and the skirt on the outer cap is folded around 25 this deformed area and pressed into engagement therewith so that the margins of both skirts assume somewhat the same general irregular shape.

Other objects will be in part apparent and in part pointed out hereinafter.

30 In the drawing:

Fig. 1 is a fragmentary side elevational view showing the closure applied to a jar.

Fig. 2 is a vertical sectional view of the closure.

Fig. 3 is a sectional view of the outer cap prior 35 to the assembly operation.

Fig. 4 is a sectional elevational view of the inner cap.

Fig. 5 is a fragmentary detail sectional view showing the manner in which the two skirts are 40 secured together.

Fig. 6 is a fragmentary sectional view taken along the line VI—VI of Fig. 5.

The illustrated form of closure consists of an inner cap 10 and an outer cap 11 adapted to be 45 telescoped one over the other and securely fastened together. These caps may well be formed of suitable sheet metal as is customary.

The inner cap consists of a circular top 12 and a depending continuous skirt 13 or attaching 50 flange, the latter provided with screw threads 14 or the like, for holding engagement with projections such as threads (not shown) on a jar 15. The lower margin 16 of the threaded skirt 13 is of somewhat greater diameter than the main 55 portion of the skirt, and, as will be noted, par-

ticularly in Figs. 2 and 5, consists of a straight depending wall 17 at the outer margin of a substantially horizontal ledge 18. This depending wall 17 is deformed preferably in a fashion to provide a continuous series of corrugations 19 or 5 ribs, which constitute part of means for securing the inner and outer caps together as will be apparent presently. If preferred, these corrugations may well be formed on the skirt of the outer cap 11.

The outer cap consists of a circular top 20 which may be of crown form or perfectly flat, and a depending continuous skirt 21. This skirt 21 is of somewhat greater depth than the threaded skirt 13 on the inner cap and is adapted to have that portion extending below the inner cap flange folded inwardly and upwardly around said depending wall 17 and then subjected to such a degree of outward pressure that it assumes to some extent, at least, the form of the corrugations 19. In this manner the two caps will be 20 positively secured together and relative rotation thereof will be impossible. Such folding of the inner cap flange also forms an internal bead 25 which gives the lower margin of the closure a finished appearance.

It is customary in the manufacture of closures of this character to suitably decorate or ornament the exterior surface of the outer cap which is perfectly smooth.

Modifications may be resorted to within the spirit and scope of the appended claims.

30 What I claim is:

1. A closure comprising an inner cap having a circular attaching flange provided with screw threads, said threads terminating at a point short of the lower margin of the flange, said flange having that portion below the threads directed outwardly and thence converging downwardly forming a continuous channel substantially L-shaped in cross-section, and an outer cap arranged over the inner cap and including a continuous flange, said flange having its lower end folded inwardly and upwardly to provide a continuous bead into which the downwardly converging portion of the attaching flange projects, said downwardly converging portion being at least in part deformed and said bead being compressed sufficiently to cause the upwardly folded portion to substantially assume the shape of the deformed areas and thereby secure the caps against relative rotation, the exterior portion of said bead having a smooth outer surface free from deformed areas or areas conforming to the deformation of said downwardly converging portion.

2. A closure for a container comprising an inner cap and an outer shell each having a top and a depending skirt, the skirt of the inner cap being provided with a spiral groove and having its edge portion corrugated, the corrugations running longitudinally of the skirt, the inner diameter of the skirt of the shell being substantially equal to the outer diameter of the corrugated portion of the inner cap, the edge por-

tion of the shell being curled over the corrugated portion of the inner cap whereby the corrugated portion of the inner skirt is securely gripped between the body and the curled over edge of the skirt of the shell, the exterior of the shell being smooth in the area opposite the corrugated portion. 5
